United States Patent

Des. 237,162
Patented Oct. 14, 1975

237,162

CAR RAMP

Jack V. Miller, Sierra Madre, Calif., assignor to
Orion Industries, Inc.

Filed Sept. 6, 1974, Ser. No. 503,947

Term of patent 14 years

Int. Cl. D12—05

U.S. Cl. D12—53

FIG. 1

FIG. 2

FIG. 3

FIG. 4

FIG. 5

FIG. 1 is a perspective view of a car ramp showing my new design;

FIG. 2 is a side elevational view thereof, the opposite side being a mirror image of the side shown herein;

FIG. 3 is a top plan view thereof;

FIG. 4 is a rear elevational view thereof; and

FIG. 5 is a front elevational view thereof.

I claim:

The ornamental design for a car ramp, substantially as shown.
